UNITED STATES PATENT OFFICE.

ALFRED Y. HARPER, OF MONTREAL, QUEBEC, CANADA.

PLUMB LEVEL.

Application filed September 10, 1925. Serial No. 55,468.

My invention relates to plumb levels of the mechanical kind in that the use of spirits is avoided, and the object of the invention is to provide a mechanism which will register 5 as required horizontal and vertical positions and in angular position.

A further object of the invention is to eliminate all springs and obtain accurate indications of the level, perpendicularity and 10 angular position of any surface or article to be constructed or which exists.

The invention also has for its object to provide a mechanical level the index of which is controlled solely by a counterweight 15 to be actuated with respect to and movable independently of the dial, for more delicate and correct indication of position.

To this end the invention may be said to consist in a case containing a dial graduated 20 in degrees of a circle, the dial being arranged upon the face plate of the case, the back plate of which is permanently fixed in parallelism with the face plate by being made the bottom of a cylinder case or otherwise 25 formed integrally with the frame in which the face plate and dial are mounted. A fine arbor is mounted at one end in a bearing in the back plate centrally thereof, and its opposite end protrudes centrally 30 through the face plate and dial in which it finds bearing while the protruding end has an index hand mounted rigidly upon it.

Between the face plate and back plate is mounted on the arbor a counterweight of 35 peculiar form in that it is of substantially the width of the interior of the case and is hung from the arbor to which it is rigidly connected by a goose neck for the purpose of giving full scope for the movement of the 40 counterweight as the angular position of the level is changed. The level thus produced is extremely sensitive.

For full comprehension, however, of my 45 invention, reference must be had to the accompanying drawings, in which similar reference characters indicate the same parts, and wherein:

Figure 1 is a face view of a plumb level constructed according to my invention;

50 Figure 2 is a transverse vertical sectional view taken on line 2—2 Figure 1, and drawn to a larger scale for clearness of illustration;

55 Figure 3 is a longitudinal sectional view taken on line 3—3 Figure 2; and

Figure 4 is a longitudinal sectional view taken on line 4—4 Figure 2, illustrating particularly the case for the mechanism of my improved plumb level, and the manner in which it is mounted in the stock. 60

In the drawings the stock is indicated at 2; it has a cavity in the form of circular bore 3 in the center of one side thereof; the outer end of this cavity or bore is enlarged to present a shoulder 4. The case for the mechanism is indicated at 5, back plate at 6, face plate at 7 and dial at 8. The fine arbor is indicated at 9 and counterweight at 10, and the goose neck connection between the counterweight and arbor at 12, while 70 the index hand is indicated at 14. The counterweight is formed with a sleeve 40 in which the arbor 9 is carried rigidly, its ends protruding to engage and bear in the back-plate 6 and fore-plate 7 through which latter it protrudes through the dial and carries the index 14. 75

As shown in Figure 2 the counterweight is substantially the full width of the interior of the case between the face plate and the back plate, the effect being that in the event of the level being jarred by being dropped, or otherwise, the counterweight will be sustained in position by the ends of the casing, and because of the close fit and relatively large form of the counterweight maximum freedom of movement is provided by an opening 15 to the atmosphere. The case is held in place by three wood screws 30 passed through countersunk screw holes 31 and 90 screwed into the stock; while the face plate is clamped in place by three machine screws 32 the heads of which overlap the edge of the face plate, for the purpose. 85

The shoulder 4 is sufficiently deep to accommodate an outwardly flared protecting plate 20 the outer rim of which is secured by screws 25 to the face of the stock, while the reduced inner rim surrounds the dial. 95

My improved level possesses maximum 100 sensitiveness because of the particular form of the counterweight and its relatively large size, while the ends of the sleeve 40 present limiting shoulders which maintain the counterweight in its proper position within the 105 case.

What I claim is as follows:

1. In a mechanical level the combination with a stock having a central cavity or bore on one side thereof; of a case adapted 110

to fit within the cavity or bore and presenting an inner closed end or back plate, a face plate closing the outer end of the case; means for securing the case within the cavity or bore; a fine arbor; means for rotatably mounting the arbor at one end in the face plate, and at its opposite end in the opposite end of the case or back plate; a dial secured rigidly to the face plate; an index hand mounted rigidly on the protruding end of the arbor; a counterweight; a goose neck connection for rigidly connecting the counterweight to the arbor.

2. A mechanical level such as claimed in claim 1 the counterweight of which is connected to the arbor by a goose neck.

3. A level such as claimed in claim 1 the actuating mechanism of which substantially completely fills the case between its ends and between the arbor and the side of the case such case having an opening to the atmosphere.

4. A plumb level consisting of a stock having a central cavity in one side thereof

the outer end of the cavity being enlarged 25 to present a shoulder; a hollow case mounted within the cavity and having an open front, said case having a peripheral flange surrounding its open front and bearing against the shoulder; means for securing 30 said flange to the shoulder; a face plate closing said open front of the case; means for securing the face plate upon the case; a dial carried by the face plate; an arbor having its ends journaled in the back of the 35 case and the face plate, the front end of the arbor extending through the face plate and dial; a counterweight connected to the arbor within the case; an indicating device mounted upon the protruding end of the arbor and an outwardly flared protruding plate secured upon the stock in position encircling the dial and concealing the surrounding portion of the case.

In testimony whereof I have signed my 45 name to this specification.

ALFRED Y. HARPER.
